Des. 183,080
Patented June 24, 1958

183,080

FLOOR TREATING MACHINE

Walter G. Ashton, Winnetka, Ill.

Application July 22, 1957, Serial No. 47,034

Term of patent 14 years

(Cl. D9—2)

Figure 1 is a perspective view of the front left side and top of a floor treating machine embodying my new design.

Figure 2 is a perspective view showing the rear right side and top of the machine.

Figure 3 is a top plan view of the machine.
I claim:

The ornamental design for a floor treating machine, substantially as shown.
